CLAIM

The ornamental design for a blower unit housing, as shown and described.

DESCRIPTION

FIG. 1 is a perspective view of a blower unit housing showing the new design, in use with exemplary ducting and motor. FIG. 2 is another perspective view of the blower unit housing of FIG. 1.

FIG. 3 is a top view of the blower unit housing of FIG. 1.

FIG. 4 is a side view of the blower unit housing of FIG. 1.

FIG. 5 is an opposite side view of the blower unit housing of FIG. 1.

FIG. 6 is a bottom view of the blower unit housing of FIG. 1.

FIG. 7 is an end view of the blower unit housing of FIG. 1; and,

FIG. 8 is an opposite end view of the blower unit housing of FIG. 1.

The broken lines in the drawing depict environmental subject matter only and form no part of the claimed design.
